UNITED STATES PATENT OFFICE.

HENRY L. R. WOLF, OF DAYTON, OHIO, ASSIGNOR TO THE AULL BROS.
PAPER & BOX CO., OF SAME PLACE.

PAPER VESSEL.

SPECIFICATION forming part of Letters Patent No. 678,606, dated July 16, 1901.

Application filed February 28, 1901. Serial No. 49,193. (No model.)

To all whom it may concern:

Be it known that I, HENRY L. R. WOLF, a citizen of the United States, residing at Dayton, in the county of Montgomery and State of Ohio, have invented certain new and useful Improvements in Paper Vessels, of which the following is a specification, reference being had therein to the accompanying drawings.

10 This invention relates to paper vessels, and is more particularly applicable to that class of paper vessels known as "pails" or "buckets" ordinarily employed as receptacles for oysters, ice-cream, and the like and formed from a blank which is folded into the desired shape.

15 The object of the present invention is to provide a bail or handle whereby the vessel may be properly supported when in use and which will not tear or disrupt the vessel in 20 its movement relatively to the body thereof or while the vessel is stored or nested.

25 To these ends the invention consists in certain novel features, which I will now proceed to describe and will then particularly point out in the claims.

In the accompanying drawings, Figure 1 is 30 perspective view of a vessel embodying my invention. Fig. 2 is a sectional view taken on the line $\alpha\alpha$ of Fig. 1. Fig. 3 is a perspective view illustrative of the prior art. Fig. 4 is a view similar to Fig. 3, illustrating the nesting of vessels constructed in accordance 35 with my invention. Fig. 5 is a detail plan section illustrating the construction of such vessels as are shown in Fig. 3. Fig. 6 is a similar view illustrating my improved construction, and Figs. 7 and 8 are respectively a 40 partial elevation and perspective view showing the disadvantages of the construction here-

45 paper vessels of the character to which my present invention is applicable are formed from blanks of paper folded into the shape desired, which is usually that of a truncated pyramid, the vessel being wider at the top than at the bottom and the lines of fold being exposed at the sides of the vessel and the bail or handle being formed of a wire pivotally connected to the sides of the vessel and serving 50 not only as a handle, but also as a means for holding the parts of the blank together.

These vessels are usually provided with a top or cover, which is an integral part of the blank, and such vessels are usually nested or placed one within the other for storage and 55 shipment, the individual vessels being completed when utilized by folding down the upper portions of the blank to form the cover and inclose the contents. A usual and well-known form of such vessels is shown in Fig. 60 3 of the drawings, which illustrates this nesting of the boxes.

In said drawings, 1 indicates the vessel, formed from a folded blank, such formation resulting in an exposed free edge between 65 the points 2 and 3, as indicated at 4, while 5 represents the wire bail or handle, the ends of which are passed through the holes of the blank, as indicated in detail in Fig. 5, and serving not only as pivotal connections for 70 the handle, but also as a means for securing the folds of the blank in position. These boxes are nested for storage and shipment as indicated in Fig. 3, and in this position the bail or handle is turned down so as to lie 75 against the body of the box. It is essential that the bail or handle should be turned toward that side of the box toward which the outer flaps are folded, as indicated in Fig. 4. This necessity arises from the fact that if the 80 bails are turned to the opposite side, as indicated in Fig. 3, the nesting of the boxes will cause the outermost flaps to slip upon the bail, as indicated in Fig. 3, and thus permit the box to be partially opened or unfolded. 85 This arises from the wedging action of the uppermost boxes inserted in the lower boxes during the nesting operation. When the bail is turned in the opposite direction, as shown in Fig. 4, this slipping of the outermost side 90 flaps on the bail is obviously prevented. The turning of the bail in the direction shown in Fig. 4 presents, however, certain difficulties. In the first place it will be seen from an inspection of Figs. 7 and 8 that when the box 95 is to be utilized the turning of the bail upward into the position where it can be used as a handle tends to cause the same to engage with the upper portion of the edges 4 of the outermost folds of the box, thereby hindering 100 the proper raising of the bail and causing it to have a tendency to tear or unfold the box.

This arises from the fact that the bail as ordinarily constructed comprises a cross-piece or handle proper, 6, and side members 7, which are bent at their ends, as shown at 8, to pass through the box to form pivots for the bail, the ends being again bent, as shown at 9, into approximate parallelism with the side members 7 to prevent the slipping out of the bail. If the parts 7 and 9 are sufficiently close to each other to tightly embrace the paper of which the box is composed, then the outer portions 7 will engage with the edges 4 of the folds, in the manner shown in Figs. 7 and 8 when the bail is raised, and such engagement is objectionable for the reasons already stated. If, on the other hand, the parts 7 and 9 are not brought close enough together to tightly embrace the paper of which the box is composed, then the parts 9 project to a considerable extent into the interior of the box, and when the boxes are nested these projecting parts engage with and tear the paper of the inserted boxes, thereby rendering them leaky and unfit for use. To overcome these objections, I propose to employ the construction shown in detail in Figs. 1, 2, 4, and 6, in which 10 represents the box, which is preferably of increasing diameter toward the top, and which is constructed from a folded blank having outer side flaps 11, presenting between the points 12 and 13 edges 14, while 15 represents the bail comprising a transverse portion 16 and side portions 17. These side portions are for the greater portion of their length at a distance apart greater than the width of the box at the top, their extremities being bent or deflected inward, as shown at 18, and then continued for a short distance parallel with the portions 17, but at a less distance from each other, as indicated at 19. These portions 19 serve to connect the portions 17 with the pivotal portions 20 of the bail, which are bent at right angles to the portions 19 and pass through the paper of which the box is composed. The ends of the bail, as indicated at 21, are again bent at right angles, so as to be parallel to the portions 19, the parts 19 and 21 bearing against the outer and inner sides of the box, respectively, and closely embracing the same, so that the parts 21 lie close to the inner wall of the box. The parts 19 are of a length less than the distance from the pivotal portions 20 to the edges 14 of the outer flaps of the box. It results from this construction that the ends of the bail embrace and hold the folded paper walls of the box for a comparatively short distance, so that the frictional contact between the ends of the bail and the box is not sufficient to materially impede the swinging up of the bail into the position which it assumes when in use.

If it were not for the bending or deflecting outward of the side portions of the bail, as indicated at 18, then these side portions would have too extended a contact with the

outer walls of the box, and the resulting friction would impede the motion of the bail. If in order to avoid this friction the inner ends 70 of the bail were not brought into close parallelism with the outer side portions thereof, then said inner ends would project to an excessive extent, as indicated at 9 in Fig. 5. Moreover, my improved construction is such 75 that the portions 17 of the bail do not come into contact with the edges 14 of the outer flaps of the box when the bail is brought into vertical position, so that the bail may be readily swung up into operative position 80 without meeting resistance and without damaging or loosening the box. I have thus provided each box with a bail which will properly accomplish its functions when the box is in use and which when the boxes are 85 nested will not tear or damage the adjacent boxes, since the parts 21 lie close to the inner side walls of the box in such a position as to permit the ready insertion and removal of other boxes. Moreover, my improved 90 construction permits the turning down of the bail on that side of the box which will prevent the opening up of the box in nesting and at the same time avoids the objections heretofore pointed out as attendant upon the 95 turning down of the bail on this side and arising from the tendency of the bail to engage the free edges of the outer folds of the box when turned up into position for use.

While my invention is particularly adapted 100 for use in connection with pails of the character described, I do not wish to be understood as limiting its application to such pails, as it is obviously capable of a wider range of use. It is obvious that when my improvement is employed with a vessel pyramidal in form and widest at its top the outward deflection of the bail at each side enables the sides of the bail to be fastened to the box below its top, where it is narrower 110 than at the top, while at the same time preventing contact between the bail and the upper portion of the pail immediately adjacent to the top, thus avoiding excessive friction at this point. Moreover, the sides of the bail 115 may be brought into parallelism as to their wider portions, thus avoiding an excessive width of bail at its top. It will thus be seen that my improvement is of special advantage in connection with vessels of pyramidal form 120 having an increasing width toward the top.

Having thus fully described my invention, what I claim as new, and desire to secure by Letters Patent, is—

1. The combination, with a folded paper 125 vessel having side flaps with exposed edges, of a bail or handle, the ends whereof pass through the side walls of the vessel to form pivots, the ends being bent up against the inside of the vessel, those portions of the bail 130 adjacent to the pivots being brought into parallelism to closely embrace the walls of the vessel, and the remaining parts of the side portions of the bail beginning below the rim

of the vessel being bent or deflected outwardly so as to be free from contact with the vessel, substantially as described.

2. The combination, with a folded paper vessel of increasing width toward the top and provided with side flaps having exposed edges, of a bail or handle, the ends whereof pass through the side walls of the vessel to form pivots, the ends being bent up against the inside of the vessel, those portions of the bail adjacent to the pivots being brought into parallelism to closely embrace the walls of the vessel, and the remaining parts of the side portions of the bail beginning below the rim of the vessel being bent or deflected outwardly so as to be free from contact with the vessel, substantially as described.

3. The combination, with a folded paper vessel having side flaps with exposed edges, of a bail or handle, the ends whereof pass through the side walls of the vessel to form

pivots, the ends being bent up against the inside of the vessel, those portions of the bail adjacent to the pivots being brought into parallelism to closely embrace the walls of the vessel, those parts of the outer side portions of the bail from the pivots toward the handle portion which are thus brought into contact with the outer side walls of the vessel being of less length than the distance from the pivots to the exposed edges of the side flaps, and the remaining parts of the side portions of the bail beginning below the rim of the vessel being bent or deflected outwardly so as to be free from contact with the vessel, substantially as described.

In testimony whereof I affix my signature in presence of two witnesses.
